UNITED STATES PATENT OFFICE.

LESTER A. WERNERY, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,172,854.

Specification of Letters Patent. Patented Feb. 22, 1916.

Application filed October 16, 1915. Serial No. 56,179.

To all whom it may concern:

Be it known that I, LESTER A. WERNERY, a citizen of the United States, residing in Brooklyn borough, in the county of Kings, 5 city and State of New York, have invented certain new and useful Improvements in Type-Writing Machines, of which the following is a specification.

This invention relates to typewriting machines, and more particularly to a device for facilitating the writing of labels or other very small work-pieces.

It is advantageous to hold the work-piece close to the platen, so that the type im- 15 pressions may be clear.

A feature of this invention is the provision of means whereby the small sheet or card may be held closely to the platen and written upon not only at the center, but 20 also very close to all edges. The means for doing this may comprise a pair of springy clips which bear upon the work-piece close to the printing line. These clips may be provided with upwardly extending 25 fingers at both their inner and outer edges. The adjacent or inner fingers lie close together, having only sufficient space between them to permit the type to strike through. These fingers are flat, and serve to protect 30 the paper from being injured as the ribbon guide vibrates up and down, and they prevent the ribbon from smudging the paper. The outer fingers are provided with flared 35 portions to prevent the sheet from fouling thereon. The top edges of the clips, from which the fingers rise, also have flared portions, to prevent the lower edge of the work-piece from fouling thereon. The clips and 40 fingers may be made of thin, springy sheet metal, and polished on their working faces.

Other features and advantages will hereinafter appear.

In the accompanying drawings, Figure 1 is a perspective view of certain parts of an 45 Underwood typewriting machine, showing my invention applied thereto. Fig. 2 is a front elevation, showing the type and ribbon vibrator and ribbon in actuated position; the ribbon being shown in dot and 50 dash lines. Fig. 3 is a side elevation, showing the relative position between the platen, the work and the clips.

In an Underwood typewriting machine, types 55 strike upwardly and rearwardly against the front face of a platen 7, or

upon the sheet thereon. An ink ribbon 8 is moved upwardly over the printing point at each type stroke by the usual mechanism, comprising a vibrator or guide 9, through which the ribbon is threaded. The work-piece is usually held to the platen by feed rolls 10 and 11. The platen is mounted on a carriage and is fed in letter-spaced direction by the usual mechanism.

A pair of clips 12 bear against the platen 65 near the printing line to hold the work-piece close to the platen. These clips may be in the form of a pair of springy tongues, secured upon the frame 13 of the machine and rising in front of the platen at either 70 side of the printing point. Near their adjoining edges, these tongues are provided with upwardly directed fingers 14, extending up beyond the printing line of the platen. These fingers are close together, 75 leaving just enough room between them for the types to pass; and they therefore hold the work-piece firmly while the types strike very close to the side edges. These fingers also serve to protect the work-sheet from 80 being injured when the ribbon vibrator is moved up and down.

To aid the fingers in the support of the work-piece, the clips are provided at their outer edges with a set of fingers 15, rising 85 from the tongues 12. Each springy tongue or clip and its fingers thereon has, at its upper part, a substantially U-shape contour, as shown in Figs. 1 and 2. These fingers also serve to hold the work-piece so that the 90 line of writing is visible to the operator, and so that the operator may easily align the work-piece by means of the scales 16, provided on flared portions 17, on the top edges of the tongues between the fingers 95 14 and 15. These scales have graduations whereby the operator may determine the number of line-spaces. The work-sheet is prevented from fouling on the paper fingers 15, by flared portions 18 provided thereon, and also on the upper edges of the tongues 12 by the flared portions 17, which also carry 100 scales. Upon their working faces the paper fingers 14 and 15 are preferably highly polished, so that when the work-sheet 105 travels with the platen in line-space and letter-feed movements of the carriage, the pressure of the paper fingers causes the work-sheet to travel with the platen. It has been found in practice that these 110

and fingers form satisfactory guides for small labels, and like work-pieces, even though the latter are traveling with the platen while the guides and fingers are stationary; in fact, the relative movement between the paper and the guide fingers is an advantage, because it enables the guide fingers to engage the paper at any of its edges regardless of the size of the paper label. Either of the middle fingers 14, it is seen, may engage the paper by a very small margin, thus enabling the type to strike almost on the edge of the work-piece; and a similar result can be obtained at the top and bottom edges of the work-piece.

Variations may be resorted to within the scope of the invention, and portions of the improvements may be used without others.

Having thus described my invention, I claim:

1. In a typewriting machine, in combination with a carriage, platen and frame, of a pair of U-shaped springy clips secured to the frame in line with each other and in position to contact with the platen, the adjacent arms of the U's being close together, and the edges of the U's being flared.

2. In a typewriting machine, the combination with a platen and a resilient paper clip comprising a pair of tongues fast to the machine frame, each of said tongues being as to its upper part of substantially U-shape, one side and the bottom edge of each of said U-shaped portions being flared.

3. In a typewriting machine, the combination with a platen and a resilient paper clip comprising a pair of tongues fast to the machine frame, each of said tongues being as to its upper part of substantially U-shape, each side of one arm of the U and the upper edge of the bottom of the U being flared.

4. In a typewriting machine, the combination with a platen and a pair of resilient paper clips secured to the frame of the machine, said paper clips each having two arms, the adjacent arms of each clip being close to the printing point, and the remote arms of the clip being flared on each side to permit adjustment of the platen and work thereon under said arm.

5. In a typewriting machine, the combination with a platen and a pair of resilient paper clips secured to the frame of the machine, said paper clips each having two arms, the adjacent arms of each clip being close to the printing point and the remote arms of the clip being flared on each side to permit adjustment of the platen and work thereon under said arm, each of said clips being provided with a gage extending between the bottoms of its two arms.

LESTER A. WERNERY.
